UNITED STATES PATENT OFFICE

170,943

BARBECUE BRAZIER

Jean O. Reinecke, Oak Park, Ill., assignor to Mell-Hoffmann Mfg. Co., Chicago, Ill., a corporation of Delaware

Application March 20, 1953, Serial No. 24,135

Term of patent 7 years

(Cl. D81—10)

To all whom it may concern:

Be it known that I, Jean O. Reinecke, a citizen of the United States, residing at Oak Park, Cook County, Illinois, have invented a new, original, and ornamental Design for a Barbecue Brazier, of which the following is a specification, reference being had to the accompanying drawing, forming a part thereof, and wherein: The figure is a perspective view of a barbecue brazier embodying my new design.

The essential features of my design reside in the portions shown in full lines.

I claim:

The ornamental design for a barbecue brazier, substantially as shown and described.

JEAN O. REINECKE,
